TRIGGER TYPE COLLAPSING TAP

William J. Hogg, Cleveland, Ohio, assignor to The National Acme Company, Cleveland, Ohio, a corporation of Ohio

Application August 20, 1943, Serial No. 499,331

16 Claims. (Cl. 10—95)

This invention relates to threading tools such as taps and dies and, more particularly, to the means for insuring the positive collapsing of the chasers upon completion of the thread cutting operation, the principal object of the invention being to provide such a device that will be positive in operation, simple in construction and inexpensive to manufacture.

In the drawings accompanying and forming a part of this specification,

Fig. 1 is a transverse vertical section of a tap with the invention applied thereto.

Fig. 2 is a section at right angles to Fig. 1.

Fig. 3 is a vertical section taken on line 3—3 of Fig. 1.

Fig. 4 is a front elevation of the tap shown in Fig. 1.

Fig. 5 is a transverse vertical section taken on line 5—5 of Fig. 2.

Fig. 6 is a transverse vertical section taken through the tap and showing the operating cam and its appurtenances.

Fig. 7 is a detail view of the cam and its associated collar.

Fig. 8 is a vertical section of the cam nested with the collar, and

Fig. 9 is a partial plan detail of the body.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawings since the invention is capable of other embodiments, and that the phraseology employed is for the purpose of description and not of limitation.

This improved tap comprises a body portion 2 having at the rear thereof a shank 3 for attachment to the holding means of a threading machine and, at the front thereof, radial slots 4 for the reception of chasers 5.

Within an axial bore 6 of the body 2 is located an axially shiftable core piece 7 having at the rear end the usual spring 8 for shifting the core piece at the proper time to retract the chasers and at the front end suitably secured thereto a tapered nose piece 9. This nose piece is provided with tongues 10 and grooves 11 for engaging similar tongues and grooves of the chasers 5. The chasers are held in the slots 4 of the body and in engagement with the nose piece 9 by means of a front plate 12. Thus, it will be observed that the axial shifting of the core piece will effect

radial shifting of the chasers to collapse them out of the work at the proper time upon completion of the thread cutting operation.

Surrounding the body 2 is an axially shiftable collar or sleeve 13 carrying toward its front end a tie bar 14 hereinafter to be more fully described and toward its rear end is provided with a circumferential slot 15 for the reception of an arcuate trigger cam or latch 16 having its front edge beveled as at 17. This cam 16 is urged outwardly by means of suitable springs 18.

Located in the rear of the collar 13 is an adjusting ring or collar 19 having suitable engagement with the body 2 for moving it back and forth properly to adjust the chasers for diameter and at its forward end encircling the collar 13 in such manner that it provides a shoulder 20 abutting the rear of the cam 16.

Surrounding the two collars 13 and 19 is an axially shiftable cap or hood 21 and secured in any suitable manner to the front end of this hood is a plate 22. A plurality of springs 23 are located between this plate 22 and collar 13, the purpose of which will be more fully explained hereinafter.

This tap is designed for attachment either to a rotary spindle, in which case the tap rotates and the work is held against rotation, or it may be attached to a non-rotatable spindle, in which case the work will rotate while the tap is held against rotation.

When the tap is attached to a rotatable spindle, this hood 21 may be provided with a circumferential groove 24 for the reception of the usual fork on the machine adapted to shift the hood back and forth at the proper time to open and close the chasers.

When the tap is attached to a stationary or non-rotatable spindle, this hood is shifted in one direction by means of a work engaging member 25 connected to the hood by means of slotted arms or fingers 26 and returned or shifted in the other direction by means of an arm or lever 27 as is usual in taps of this nature and, therefore, a detailed description thereof is not thought necessary herein.

Projecting inwardly on the inside wall of the hood 21 is a circumferential projection 28 having its rear edge 29 beveled to correspond with the bevel of the cam 16 and the front edge 30 forming an abutment shoulder for the projecting ends of the tie bar 14.

As before stated, this tie bar 14 is carried by the collar 13 and is adapted to extend through the elongated slots 31 of the body 2 and a some-

what shorter elongated slot 32 of the core piece 7.

The operation of the tap is as follows:

When the thread cutting operation has been completed the hood 21 is shifted axially either by a fork on the machine or by the work engaging member 25 and the arms 26. This shifting of the hood causes the inwardly extending projection 28 of the hood 21 to depress the cam 16 due to the cooperating beveled surfaces 29 and 17 of the hood and cam, respectively.

When this cam is depressed below the shoulder 20 of the adjusting sleeve 19, the spring 8 ordinarily pulls back the core piece 7 and collar 13 but, under heavy cutting action of the chasers or if the chasers hit a shoulder while threading, frequently they tend to set up a torque on the sides of the slots and also on the core piece 7 that would tend to prevent the core from receding freely and thus prevent collapse of the chasers.

Such a situation is overcome in the present construction because the hood, in moving back relative to the body before it fully depresses the cam 16, sets up a tension in the springs 23 because, at this time, the collar is held against axial movement. However, when the cam 16 is depressed below the shoulder 20 of the ring 19, since there is no cutting strain on this part of the tap, the collar 13 will be moved freely by the springs 23 and this movement will carry the tie bar 14 in the slot 32 of the core until it contacts the core at the end of the slot, when it will give the core a kick action and insure proper withdrawal of the core under the operation of the spring 8.

Thus, it will be seen that this invention provides a positive action in the collapse of the chasers due to the sudden kicking action of the tie bar on the core piece which will offset any torque set up and insure the proper withdrawal of the chasers from the work.

To reset the tap, either a fork on the machine acting in the groove 24, or the hand lever 27 may be used and since the shoulder 30 of the projection 28 contacts the tie bar 14, forward movement of the hood will carry the tie bar 14, collar 13 and core piece 7 forward relative to the body until the trigger cam 16 passes the shoulder 20 of the adjusting ring 19 whereupon the springs 18 will force the cam 16 outwardly to the position shown in Fig. 1. When this trigger cam 16 has been forced outwardly, the spring 8 will cause the core piece 7, collar 13 and cam 16 all to be held back to the proper position and the chasers will be accordingly reset for the proper cutting position in conformity with the setting of the size adjusting ring 19.

It is to be understood that, by describing in detail herein any particular form, structure or arrangement, it is not intended to limit the invention beyond the terms of the several claims or the requirements of the prior art.

Having thus explained the nature of my said invention and described a way of constructing the same, although without attempting to set forth all of the forms in which it may be made, or all of the modes of its use, I claim:

1. A threading tool having a body, chasers carried thereby, means for normally retracting the chasers at the end of the thread cutting operation, and supplemental means for insuring the retraction of the chasers, said supplemental means comprising a sleeve, a trigger for holding it against movement relative to the body during

the thread cutting operation, means for releasing the trigger to permit movement of said sleeve upon completion of the thread cutting operation, and means for moving the sleeve and including a spring activated member extending transversely of the body.

2. A threading tool having a body, chasers carried thereby, means for normally retracting the chasers at the end of the thread cutting operation, and supplemental means for insuring the retraction of the chasers, said supplemental means comprising a sleeve, a trigger for holding it against movement relative to the body during the thread cutting operation, means for releasing the trigger to permit movement of said sleeve upon completion of the thread cutting operation, and means for moving the sleeve, said last means comprising spring means and said sleeve shiftable relative to the normal retracting means and provided with means for kicking the normal retracting means into operation.

3. A threading tool having a body, chasers carried thereby, means for collapsing the chasers at the end of the thread cutting operation, an axially movable sleeve carried by the body, means for holding the sleeve against movement during the thread cutting operation and operative to permit movement upon the completion thereof, means carried by the sleeve effective to insure operation of the collapsing means, means for initially moving the sleeve independently of the collapsing means, and means connecting the sleeve and collapsing means whereby upon failure of the collapsing means to operate the sleeve will be shifted to kick the collapsing means and initiate movement thereof, said connecting means comprising a spring actuated tie bar carried by the sleeve and collapsing means and having a limited movement relative to the collapsing means.

4. A threading tool having a body, chasers carried thereby, a core piece shiftable relative to the body and having engagement with the chasers for retracting them upon completion of the thread cutting operation, means for normally retracting the core piece, and supplemental means for insuring retraction of the chasers and including a spring actuated member extending transversely of and shiftable in the core piece.

5. A threading tool having a body, chasers carried thereby, a core piece shiftable relative to the body and having engagement with the chasers for retracting them upon completion of the thread cutting operation, and supplemental means for insuring retraction of the chasers, said supplemental means comprising a sleeve, a trigger for holding it against movement relative to the body during the thread cutting operation, and means for releasing the trigger to permit movement of said sleeve upon completion of the thread cutting operation and means for moving the sleeve, a tie bar carried by the sleeve and extending into and having a sliding connection with the core piece whereby upon failure of the core piece to shift, the sleeve will have a limited movement relative thereto to kick the core piece and initiate movement thereof, and means for moving said sleeve and thereby the tie bar to kick the core piece.

6. A threading tool having a body, chasers carried thereby, a core piece shiftable relative to the body and having engagement with the chasers for retracting them upon completion of the thread cutting operation, and supplemental

means for insuring retraction of the chasers, said supplemental means comprising a sleeve, a trigger for holding it against movement relative to the body during the thread cutting operation, means for releasing the trigger to permit movement of said sleeve upon completion of the thread cutting operation, and means for moving the sleeve, a tie bar carried by the sleeve and extending into and having a sliding connection with the core piece whereby upon failure of the core piece to shift, the sleeve will have a limited movement relative thereto to kick the core piece and initiate movement thereof.

7. A threading tool having a body, chasers carried thereby, a core piece shiftable relative to the body and having engagement with the chasers for retracting them upon completion of the thread cutting operation, and supplemental means for insuring retraction of the chasers, said supplemental means comprising a sleeve, a trigger for holding it against movement relative to the body during the thread cutting operation, a shiftable hood having engagement with said trigger for releasing it to permit movement of the sleeve upon completion of the thread cutting operation, and means for moving the sleeve, a spring actuated tie bar carried by the sleeve and extending into and having a sliding connection with the core piece whereby upon failure of the core piece to shift, the sleeve will have a limited movement relative thereto to kick the core piece and initiate movement thereof.

8. A threading tool having a chaser carrying body, a core piece shiftable relative to the body and having engagement with the chasers for retracting them upon completion of the thread cutting operation, means for shifting the core piece, means for preventing movement of the core piece during the thread cutting operation and permitting such movement upon completion thereof, and supplemental means for insuring retraction of the chasers and comprising spring actuated means located transversely to the core piece and having a limited movement relatively thereto.

9. A threading tool having a chaser carrying body, a core piece shiftable relative to the body and having engagement with the chasers for retracting them upon completion of the thread cutting operation, means for shifting the core piece means for preventing shifting thereof during the thread cutting operation and permitting such shifting upon completion thereof, and supplemental means for insuring shifting of the core piece and including a spring actuated member extending transversely of and shiftable in the core piece.

10. A threading tool having a chaser carrying body, a core piece shiftable relative to the body and having engagement with the chasers for retracting them upon completion of the thread cutting operation, means for shifting the core piece, means for preventing shifting thereof during the thread cutting operation and permitting such shifting upon completion thereof, and supplemental means for insuring shifting of the core piece, said supplemental means comprising a shiftable sleeve held against movement relative to the body during the thread cutting operation and shiftable upon completion thereof, means for shifting it, and means for connecting the sleeve and core piece whereby upon failure of the core shifting means the sleeve will be shifted to engage the core piece and kick the core and initiate movement thereof.

11. A threading tool having a chaser carrying body, a core piece shiftable relative to the body and having engagement with the chasers for retracting them upon completion of the thread cutting operation, means for shifting the core piece, means for preventing shifting thereof during the thread cutting operation and permitting such shifting upon completion thereof, and supplemental means for insuring shifting of the core piece, said supplemental means comprising a shiftable sleeve held against movement relative to the body during the thread cutting operation and shiftable upon completion thereof, means for shifting it, and means for connecting the sleeve and core piece whereby upon failure of the core shifting means the sleeve will be shifted to kick the core and initiate movement thereof, said connecting means comprising a tie bar carried by the sleeve and engaging the core piece and having a limited movement relative to the core.

12. A threading tool having a body, chasers carried thereby and means for collapsing the chasers out of the work upon completion of the thread cutting operation, said means comprising a pair of members stationary relative to the body during the thread cutting operation and shiftable relative thereto upon completion thereof, means normally operable to shift both of said members in unison, means carried by one of said members and having sliding connection with the other of said members, and means operable to shift one of said members independently of the other a predetermined distance to kick the normally operable means into action upon failure of said normally operable means to shift the members in unison.

13. A threading die having a body, chasers carried thereby, a core piece stationary relative to the body during the thread cutting operation and shiftable relative thereto upon completion of the thread cutting operation for retracting the chasers, means for shifting the core piece, and supplemental means for insuring retraction of the chasers and comprising a sleeve, means carried by the sleeve and extending into and having a sliding connection with the core piece and means for shifting the sleeve a predetermined distance relative to the core piece upon failure of the core piece to shift to kick the core piece and start shifting thereof.

14. A threading tool having a body, chasers carried thereby, a pair of members shiftable relative to said body for collapsing the chasers upon completion of the threading operation, means for shifting each of said members, means for holding the members against shifting, means for releasing the holding means to permit such shifting, means carried by one of said members and extending into and having sliding engagement with the other member, the means for shifting one of said members normally operable to shift both of said members in unison, and the means for shifting the other of said members operable to shift said member independently a predetermined distance to kick said other member and initiate operation of said normally operable means upon failure of said normally operable shifting means.

15. A threading tool having a body, chasers carried thereby, a core piece shiftable relative to the body and having engagement with the chasers for shifting them and including means for primarily retracting the chasers upon completion of the thread cutting operation and supplemental

means for insuring retraction of the chasers and comprising a member having a sliding engagement with the core piece and means for shifting said member thereby to kick the core piece at a predetermined time.

16. A threading tool having a body, chasers carried thereby, primary means shiftable relative to the body and cooperating with the chasers for normally retracting the chasers at the end

of the thread cutting operation, and supplemental means for insuring retraction of the chasers and comprising a shiftable member co-operating with said primary means to impart a kick thereto upon the failure of said primary means to act, and spring means for shifting said member to effect such kick.

WILLIAM J. HOGG.
